UNITED STATES PATENT OFFICE.

MARTIN THUM, OF ROCHESTER, NEW YORK, ASSIGNOR TO LANGSLOW FOWLER COMPANY, OF ROCHESTER, NEW YORK, A CORPORATION OF NEW YORK.

CHAIR.

1,213,299.

Specification of Letters Patent. Patented Jan. 23, 1917.

Application filed September 30, 1912. Serial No. 723,115.

To all whom it may concern:

Be it known that I, MARTIN THUM, a citizen of the United States, and a resident of Rochester, in the county of Monroe and State of New York, have invented certain new and useful Improvements in Chairs; and I do hereby declare the following to be a full, clear, and exact description of the same, reference being had to the accompanying drawings, forming a part of this specification, and to the reference-numerals marked thereon.

My invention relates to chairs, having reference particularly to that class of chairs used by school children to serve both as a chair and desk, and it has for its object to provide a novel and improved construction that will efficiently serve the purposes of a chair and desk, having provision for holding books and utensils, and also for supporting any books or papers while the student is working.

A further object of my invention is to construct the parts so that they may be conveniently adjusted to different sizes, so that a standard chair may be used.

To these and other ends the invention consists in certain improvements and combinations of parts all as will be hereinafter more fully described, the novel features being pointed out in the claims at the end of the specification.

In the drawings: Figure 1 is a side elevation of a chair embodying a preferred form of my invention; Fig. 2 is a view in front elevation of the same; Fig. 3 is a plan view; Fig. 4 is a sectional view of the support, or receptacle, showing it open; Fig. 5 is a detail view in elevation of the adjustable connection between the work table and its support; Fig. 6 is a sectional view on the line 6^a—6^a of Fig. 5; Fig. 7 is a sectional view on the line 7^a—7^a of Fig. 2, and Fig. 8 is a sectional view on the line 8^a—8^a of Fig. 2.

Similar reference numerals throughout the several figures indicate the same parts.

According to the herein disclosed embodiment of my invention, 1 designates the base on which is adjustably supported the seat portion 2, the adjustable connection between the base and seat portion being of any convenient form known in this class of devices. The seat portion 2 carries the standard 3 on which is mounted the back portion 4, hav-

ing adjustable connection with the standard in any suitable manner.

The seat portion 2 carries a support, or receptacle 5 on which is mounted a work table 6, in a manner that I will describe presently. The receptacle 5 is preferably formed as shown in Fig. 4, and constitutes a receiver for books and utensils when they are not in use. To this end, it is provided with a base or bottom portion 7 upon which is pivoted a holder 8, the latter having a side portion 9 constituting a cover for the receptacle. 10 is a stop arranged within the receptacle, for limiting the outward movement of the holder 8 and adapted to engage the inner wall of the latter. The holder is so pivoted upon the base portion 7 of the receptacle that it is retained in extreme open or closed position by its own weight, and when it is closed, it may be opened by applying pressure against the lower end of the wall 9.

The work table is preferably arranged on the support or receptacle 5, as previously mentioned, and to this end, the latter is provided with a post 11 which is mounted in the brackets 12 secured to the support. The post 11 carries at its upper end a laterally extending rod 13, which is pivotally mounted in brackets 14 secured to the under side of the work table.

15 is a brace which extends through the post 11, and is attached at its ends to the rod 13 so as to hold the latter rigidly in position on the post. In order to hold the work table in various positions, I provide an adjustable connection between it and the support, and to this end, the post 11 carries an upstanding rod 16, pivotally connected thereto, and having a pin or projection 17 for a purpose that will presently appear. The work table is provided with a pivotally mounted bracket 18 within which is rotatably supported the sleeve 19, the latter being cut away and provided with a rack or toothed surface 20 which is arranged for engagement with the aforementioned projection 17 whereby the sleeve 19, and with it the work table, may be raised to different vertical positions. In order to effect this adjustment, the rotatable sleeve 19 carries the crank arm 21 with which is connected a push rod 22, held in normal position by means of the spring 23, and carrying a finger-piece

24 by which it is manipulated when it is desired to turn the sleeve in order to change the position of the work table.

To hold the post 11 in fixed position on 5 the support 5, there is provided a clamping collar 25 which surrounds the post 11, as shown in Figs. 1 and 7, and carries a neck portion 26 projecting into the opening 27 of the receptacle and fixedly attached to the 10 rod 28 in any desirable manner as by means of the pin or rivet 29. The rod 28 extends through the support 5 and is threaded at its free end, while 30 is an adjusting nut in engagement with the threaded end of 15 the rod 28. By turning the adjusting nut 30 upon the rod 28, the clamping collar is drawn inwardly toward the receptacle 5, forcing the post 11 against the edges of the brackets 12 and holding it rigidly in 20 adjusted position. By loosening the nut 30, the post 11 may be moved upwardly or downwardly to adjust it to different vertical positions. The support or receptacle 5 may be attached to the seat portion 2 in 25 any convenient manner and in the present embodiment, I have shown brackets 31 for this purpose, these being suitably attached to the seat and to the support.

I claim as my invention:

30 1. In combination with the seat portion of a chair, a receptacle supported thereon, a post slidable in guides at the front of the receptacle, a work table carried by said post, clamping means engaging said post and 35 pressing it against its guides, a rod connected to said clamping means and extending through the receptacle to the rear thereof, and means at the rear of the receptacle for adjusting said rod and the clamping 40 means with relation to the post.

2. In combination with the seat portion of a chair, of a post associated therewith, a work table pivotally mounted on the post, a rod pivotally connected to the post intermediate 45 its ends, a sleeve rotatably and pivotally con-

nected with the work table in slidable engagement with said rod, cooperating projections on the rod and sleeve adapted to normally hold said members in locked engagement one with the other, an arm connected with the sleeve and a spring controlled member pivotally connected with said arm for effecting rotation of the sleeve to permit adjustment of the same upon said rod. 50

3. An adjustable chair comprising a seat; a support mounted thereon, a post slidable in guides upon the support, clamping means engaging the post arranged to press the same against its guides, a work table pivotally mounted on the post, a rod pivotally connected to the post intermediate its ends, a sleeve rotatably and pivotally attached to the work table having slidable engagement with said rod and adapted to be normally held in locked engagement therewith, an arm connected with the sleeve and a spring controlled member pivotally connected with said arm for effecting rotation of the sleeve to permit adjustment of the same upon the rod. 60

4. In combination with the seat portion of a chair, of a post associated therewith, a work table pivotally mounted on said post, a rod pivotally connected to the post intermediate its ends, a sleeve rotatably and pivotally arranged on the work table having slidable engagement with said rod and adapted to be held in locked relation therewith, an arm carried by the sleeve, a bracket on the work table, an actuating rod connected to said arm and movable within an opening in the bracket, and means for retaining the actuating rod in normal position whereby the sleeve is held in locking engagement with the first mentioned rod. 70 75 80 85
